CRAYON OR THE LIKE HOLDER AND FEEDING TUBE

Gilbert B. Knuff, Cleveland, Ohio

Application December 10, 1948, Serial No. 64,651

2 Claims. (Cl. 120—13)

1

My invention relates to certain new and useful improvements in holders or dispensing tubes for crayon, chalk or like marking or drawing devices.

It is an object of my invention to provide an improved holder of the type aforesaid which will protect the hands of the person using the same from contact with the chalk, crayon, etc. carried thereby.

A further object of my invention is to provide a holder of the type described which eliminates breakage of the object carried thereby.

Another object of my invention is to provide an improved holder of the type aforesaid which will be composed of but a few operating parts, subject to economical production, and highly efficient in use.

The object of the invention may be realized by the means described in detail in the following specification, in which specification reference will be made to the accompanying drawings, showing by way of example, a preferred embodiment of the inventive idea.

In the drawings:

Fig. 1 is an enlarged vertical view, certain portions being cut away for clarification and other portions being sectioned of the holder of my invention, a portion of a crayon carried being shown.

Fig. 2 is a vertical plan view of the holder dispensing tube of my invention.

Fig. 3 is a view taken from the line 3—3 of Fig. 2.

Fig. 4 is a top plan view of locking means adapted to be associated with the holder of Fig. 2.

Fig. 4a is a side plan view of the locking means of Fig. 4;

Fig. 4b is an end plan view of the locking means of Fig. 4;

Fig. 5 is an enlarged view of the end closure element or cap shown in Fig. 1;

Fig. 5a is a side plan view of the closure element of Fig. 5;

Fig. 5b is a bottom plan view of the closure element of Fig. 5;

Fig. 6 is an enlarged view of a section of the holder of the crayon and locking means of Fig. 4;

Fig. 7 is an enlarged fragmentary view illustrating the muzzle end of the staff of Figs. 1 and 2.

Referring now to the drawings in all of which like parts are designated by like reference characters, at 10, I show a cylindrical dispensing tube

2

or holder, which in the preferred form of my invention illustrated herein, is employed as a crayon or chalk holder and dispenser, the use of a crayon being illustrated herein. The holder 10 is provided with a longitudinally extending slot 11, arcuate spaced notches 12 opening into said slot at spaced intervals at one side of said slot. The slot 11, preferably extends from the closed end 13 of the holder to a point adjacent the muzzle end 14 of the holder. Locking means 15, as best illustrated in Figs. 4, 4a, 4b, and Figs. 1 and 6 comprise short plastic rod portion 16 and a substantially narrow elongated handle portion 17 connected to said rod 16 by means of a pair of spaced lugs 18. The said rod portion 16 of the locking means is adapted to be inserted within the tube 10, the diameter of the rod 16 being slightly less than the inner diameter of the tube, and the lugs 18 are of such dimensions as to ride in the slot 11, the handle 17 protruding upwardly therefrom so that the locking means may be manually and reciprocably moved in the slot, the same being adapted to be rocked into locking engagement by means of the placement of the lugs 18 into any adjacent pairs of the notches 12. An enclosure cap 19 having a cylindrical disc 20, a key 21 and a projecting stem portion 22 associated therewith is adapted to be projected within the outer end 13 of the tube 10, the key 21 riding in the end of the slot 11 and the disc 20 closing the open end of the tube.

The muzzle end of the holder is provided with a plurality of slots 22, preferably three in number, adjacent the swaged-in end portions 23 of the muzzle.

The holder 10 is preferably formed of plastic material, also a light weight metal, such as aluminum or other materials might be used, and the holder, in the form shown herein, is of such diameter as to enable the supplier or operator to telescope a crayon therein. The outer diameter of the ordinary child's crayon is slightly less than the inner diameter of the holder 13 and the inner diameter of the tube in the muzzle is of slightly less diameter than that of the remainder of the holder. Hence, the holder is adapted to snugly receive the crayon at the necked-in portion 23 thereof and to hold the crayon in spaced relation in the remainder of said holder.

It will be understood that my invention may be adapted for use as a crayon, chalk or artist's marking tool and that according to its application the dimensions will be varied.

In operation, when the crayon or other mate-

rial is used, and the user desires to eject a portion of the crayon forward to replace what has been used, the user grasps the handle 17 and rotates the same in a manner to rotate the lugs 18 out of locked engagement within the arcuate notches and into the elongated runway 11, and then pushes, by means of the handle operated pusher rod 16, which contacts the material to be fed therethrough, such stick material forward. At the desired forward position, and when sufficient material protrudes out of the muzzle end of the holder, the handle and lugs are rotated back into engagement with a forward pair of notches and the pusher rod is locked in this position.

The crayon or other stick material carried by and optionally progressively fed by the tubular holder, is maintained within the tubular holder by its clamping engagement with the swaged muzzle end of the holder. Said swaged end portion however is adapted to expand sufficiently, by virtue of the provision of the slots 22, to permit the crayon or other stick material, when same is pushed forwardly by the pusher element 16, to move forwardly without undue pressure thereon and eliminates any scraping or abrasion of the crayon or the like.

I am aware that numerous and extensive departures from the embodiment herein disclosed may be made by way of materials employed and dimensions used as well as various other departures, but it is to be understood that these may be made without departing from the spirit of my invention and the scope of the appended claims.

I claim:

1. A holding device for crayons or the like comprising a tubular holder of substantially light material, said holder being provided with a muzzle end, said muzzle end having a portion of relatively less diameter than the remainder of the holder portion, an elongated longitudinally disposed keyway in the holder extending approximately from the muzzle end thereof to the opposite end of the holder, notches disposed at one side of said keyway and communicating therewith, said notches having a constricted portion adjacent said keyway, a guide telescoped within the holder and adapted to have reciprocal movement within the keyway, said guide carrying means protruding through said keyway and being manually reciprocably and laterally movable within the keyway, and into selective locking

engagement with said notches, the said muzzle end of the holder being slotted throughout its length and opened at the outer end thereof, whereby when a crayon element whose outside diameter is slightly greater than the diameter of the muzzle portion is projected into the muzzle end of the holder, said crayon is yieldably and expansibly received and retractively gripped by the relatively embracing portions of the muzzle.

- 5 2. A holding device for crayons or the like comprising a tubular holder of substantially light material, said holder being provided with a muzzle end, said muzzle end having a portion of relatively less diameter than the remainder of the holder portion, an elongated longitudinally disposed keyway in the holder extending approximately from the muzzle end thereof to the opposite end of the holder, notches adjacent said keyway and communicating therewith, a guide telescoped within the holder and adapted to have reciprocal movement within the keyway, said guide carrying means protruding through said keyway and being manually reciprocably movable within the keyway and into selective locking engagement with said notches, the said muzzle end of the holder being slotted throughout its length and opened at the outer end thereof, whereby when a crayon element whose outside diameter is slightly greater than the diameter of the muzzle portion is projected into the muzzle end of the holder, said crayon is yieldably and expansibly received and retractively gripped by the relatively embracing portions of the muzzle.

GILBERT B. KNUFF.
